UNITED STATES PATENT OFFICE.

EDWIN N. CHANDLER, OF BROCKTON, MASSACHUSETTS, ASSIGNOR TO AMERICAN SUPPLIES COMPANY, OF BOSTON, MASSACHUSETTS, A CORPORATION OF MASSACHUSETTS.

FORM FOR TREEING, &c., SHOES.

SPECIFICATION forming part of Letters Patent No. 793,988, dated July 4, 1905.

Application filed February 23, 1904. Serial No. 194,638.

To all whom it may concern:

Be it known that I, EDWIN N. CHANDLER, a citizen of the United States, residing at Brockton, in the county of Plymouth, State 5 of Massachusetts, have invented a certain new and useful Improvement in Forms for Treeing, &c., Shoes, of which the following is a specification, reference being had therein to the accompanying drawings.

- 10 The invention consists in a form of novel and improved character and construction for use in supporting shoes while being treed or ironed and during the performance of the like operations.
- 15 The invention consists, more especially, in a form for the purpose stated characterized by having a self-adjusting foot portion possessing capacity to adapt itself automatically to the size of the shoe which is applied to the 20 form, whereby one form of a given style is rendered capable of being employed in connection with various sizes of shoes of such style.

An embodiment of the invention is shown 25 in the accompanying drawings, in which—

Figure 1 shows in side elevation a form containing the said embodiment of the invention. Fig. 2 shows separately in side elevation the ankle or leg and heel portions 30 of the form. Fig. 3 is an end elevation of the ankle or leg and heel portions shown in Fig. 2. Fig. 4 is a top view of the said ankle or leg and heel portions. Fig. 5 is a view showing, detached, the foot portion in longitudinal section. Fig. 6 is a view in vertical section on line 6 6 in Fig. 4.

Having reference to the drawings, the ankle or leg portion (hereinafter termed "leg portion" or "leg-piece") of the form which 40 is shown in the drawings is designated 1. The heel portion, which is connected with the said leg portion, is designated 2. At 3 is the fore part or foot portion. The said fore part or foot portion comprises a shank portion, a toe portion, and an instep portion, and in order that it may constitute a support and backing for the upper of a shoe suitable for

enabling the operations of treeing and ironing to be properly performed the said fore part or foot portion is made with a smooth 50 and uniform unbroken exterior surface. In practice the leg portion will be fitted for application and connection to a support in a treeing-machine in any usual or approved manner.

55

In carrying the invention into effect the foot portion 3 is formed separately from the leg and heel portions and is in sliding connection with the leg-piece in a manner permitting movement of the foot portion in the 60 direction of the length thereof with relation to the leg and heel portions. In the present embodiment of the invention the top of the foot portion and the end of the leg portion fit together along the line 4, Fig. 1. The 65 manner and means of connecting the foot portion with the leg portion so as to permit the foot portion to have the relative movement which is referred to above in the direction which has been stated may vary in practice. I have shown a detachable connection comprising a pair of elongated hooks 5, 5, which in the present instance are formed on a plate that is applied to one of the parts, herein the leg portion, the other of the parts, 75 herein the foot portion, being longitudinally slotted at 6, Fig. 5, for the reception of the said hooks and having pins 7, 7, which extend across the slot in position to be engaged by the hooks. When the hooks are entered 80 within the slot, as in Fig. 1, they serve to hold the parts from lateral displacement with relation to each other. The engagement of the hooks with the pins prevents the foot portion from becoming disconnected 85 from the leg portion until the foot portion is operated to disengage the pins from the hooks. The length of the hooks is sufficient to permit a considerable extent of movement of the foot portion in the direction of its 90 length before the pins pass beyond the free extremities of the hooks.

For the purpose of rendering the foot portion automatically adjustable in the direc-

- tion of its length to enable the same to fit different sizes of shoes which may be applied to the form, I combine with the foot portion and with the remainder of the form a spring 5 or springs acting with a tendency to impel the foot portion in the direction of its length with relation to the said remainder. The manner of applying the spring or springs and of causing the tension of the same to act 10 with a tendency to extend the foot portion in the direction of its length may vary in practice without involving a departure from the principles of the invention. In the illustrated embodiment of the invention I employ 15 a pair of oppositely-located springs 8 8, Fig. 6, and in connection therewith a pair of pins or plungers 9 9. The said springs and pins or plungers are contained in holes or chambers which are formed for the reception 20 thereof in one of the portions of the form, the spring acting with a tendency to project the pins or plungers from the said holes or chambers and the outer ends of the said pins or plungers engaging with a proximate sur- 25 face of the relatively movable portion of the form. Herein the holes or chambers are formed in the heel portion 2 and the outer ends of the pins or plungers act against the rear end of the foot portion 3.
- 30 In the use of the invention, the parts of the form being assembled in proper condition, a shoe requiring to be treed or ironed is applied in usual manner to the form, and then the required operation is performed 35 thereon. The shoe having been slipped upon the exterior of the form, the spring or springs will operate to extend the foot portion of the form so as to cause the same to occupy properly the forward portion of the interior of 40 the shoe. The tension of the spring or springs will be proportioned in degree to cause the foot portion of the form to fit snugly in place within the forward portion of the shoe without straining or stretching 45 the latter. The extent of the relative movement which is permitted the foot portion with reference to the leg and heel portions is sufficient to enable the form to accommodate itself to a range comprising several different 50 sizes of shoes. The number of sizes to which the form may be thus adapted may vary in practice.
- 55 While in some cases the foot portion may be permanently connected with the leg portion in such manner as to permit relative movement in effecting self-adjustment to accommodate different sizes of shoes, as aforesaid, I prefer to apply the foot portion to the leg portion in a manner enabling the foot 60 portion to be detached from the leg portion

when desired. The object of this is to enable a foot portion suitable for use in connection with a given range of sizes of a certain style to be replaced by a foot portion suitable for use in connection with another range 65 of sizes of the said style. The detachability also permits a foot portion of one style to be replaced by a foot portion of a different style.

What I claim as my invention is—

1. A treeing-form comprising a leg-piece with connected heel portion, a longitudinally-movable fore part consisting of a shank portion, a toe portion, and an instep portion, and having a smooth and uniform unbroken 75 exterior surface suitable for the performance of treeing and ironing operations, and a spring operating with a tendency to extend the said fore part in the direction of the length of the latter relative to the said leg- 80 piece and its heel portion.

2. A treeing-form comprising a leg-piece with connected heel portion, a fore part in readily-detachable connection with said leg-piece, longitudinally movable with relation 85 thereto consisting of a shank portion, an instep portion, and a toe portion, and having a smooth and uniform unbroken exterior surface suitable for the performance of treeing and ironing operations, and a spring operat- 90 ing with a tendency to extend the said fore part in the direction of the length of the latter relative to the said leg-piece and its heel portion.

3. A treeing-form comprising a leg-piece 95 with connected heel, a fore part having a sliding fit upon the said leg-piece, a plate applied to one of said parts, a pin or pins applied to the other thereof and in sliding engagement with the said plate, and a spring 100 operating with a tendency to extend the fore part in the direction of the length of the latter upon the said leg-piece.

4. A treeing-form comprising a leg-piece with connected heel, a fore part having a 105 sliding fit upon the said leg-piece, one or more elongated hooks applied to one of the said parts, a corresponding number of pins applied to the other part and having sliding engagement with the said hook or hooks, and a spring operating with a tendency to extend the fore part in the direction of the length of the latter upon the said leg-piece.

In testimony whereof I affix my signature in presence of two witnesses.

EDWIN N. CHANDLER.
